UNITED STATES PATENT OFFICE.

WILLIAM J. KNOX, OF DUBOIS, PENNSYLVANIA.

PIN LIFTER FOR CAR COUPLINGS.

Application filed December 27, 1921. Serial No. 525,221.

To all whom it may concern:

Be it known that I, WILLIAM J. KNOX, a citizen of the United States, and a resident of Dubois, in the county of Clearfield and 5 State of Pennsylvania, have made a new and useful Invention in Pin Lifters for Car Couplings, of which the following is a specification.

The invention relates to pin lifters for 10 car couplers. It has for its main objects the provision of an improved device of very cheap, simple construction; (1) which cannot be disengaged from the coupler lock pin without removing the rocker shaft (which 15 is bolted or otherwise more or less permanently secured to the car body) from such car body; (2) which, aside from the securing brackets, can be made throughout from one size of ordinary merchant rod; and 20 which can be easily assembled and applied to practically all existing car constructions having the standard Janey coupler. One embodiment of the invention is shown in the accompanying drawings wherein:

25 Figure 1 is a partial plan view at the end of a car with the uncoupling or lifting device in position thereon. Fig. 2 is a partial end view of the construction of Fig. 1. Figs. 3 and 4 are side elevations of the 30 coupler and the pin lifting device, Fig. 3 showing the parts in locked position and Fig. 4 in unlocked position with the lock pin of the coupler in its uppermost position. Figs. 5 and 6 are detail views of the 35 connecting pin. And Fig. 7 is a plan view of the arm at the end of the rocker shaft.

Referring to the drawings, 1 is the end 40 of a car structure provided with a pair of brackets 2, 3, bolted or otherwise secured to the car body. 4 is a coupler of the Janey type having the usual lock pin 5, such lock pin having an interlocking engagement at its lower end in the coupler cavity (not shown but common in couplers of this type) 45 to prevent the entire withdrawal of the pin from the coupler, Fig. 4 showing the lock pin at the upper limit to which its stop means permits it to go. The coupler rocker shaft which is carried by the brackets 2 and 50 3 is made up of ordinary round bar iron and comprises the horizontal portion 6, the handle 7, and the lifting arm 8 provided at its end with the eye 9, such eye being somewhat elongated as indicated in Fig. 7. The 55 coupler lock pin 5 is provided with an eye 10 and between this eye and the eye 9 of

the lifting arm is a U shaped connecting pin, which is the particularly novel feature of the device.

The connecting pin comprises the vertical 60 leg 11 (Fig. 5) having the head 12 at its upper end and the partial eye 13 at its lower end and the inclined leg 14.

The parts are assembled, before the 65 brackets 2 and 3 are applied to the car, the connecting U pin being slipped through the eye 9 in the arm 8 and then through the eye 10 of the lock pin 5. The brackets 2 are now applied to the car. The space at 15 on the connecting pin (Fig. 5) is slightly 70 wider than the diameter of the rod from which the rod 6, 8 is made while the space at 16 is slightly greater than the combined diameters of the rod 6, 8 and that of the material of the eye 10 which permits the 75 ready assembling as above described.

When the parts are assembled and the rod 6 secured to the car, the coupler lock pin, the U connecting pin and the arm 8 cannot be disconnected. The upward movement of the 80 pin 5 is limited by the engagement of its lower end in the coupler cavity, so that with such pin held in its upper position, it cannot be disengaged from the leg 14 of the connecting pin because of the length of 85 such leg, extending up as it does, to a point adjacent the head 12. The connections between eyes 9 and 10 are such that free relative movement is permitted, so that the 90 coupler may move sidewise, longitudinally 90 and up and down without any binding of or injury to any of the connecting parts. The elongated eye 9 contributes to this freedom of movement. The parts are all of simple construction, and the rocker shaft and 95 connecting pin may be cheaply made from ordinary round iron by bending and forging. Other advantages incident to the structure will be readily apparent to those skilled in the art.

100 What I claim is:

1. In combination in a lifting or release device for the lock pin of a coupler having a limited upward movement, a rock shaft adapted to be secured to a car body and provided at its inner end with a lifting arm having a limited downward movement and having at its free end an eye, a connecting pin having a vertical portion headed at its upper end extending through the eye and 105 having its lower portion recurved for passing through the eye of the coupler lock pin, 110

2
and extended upwardly to a point adjacent the head on the vertical portion.

2. The combination with a coupler of the Janey type having a lock pin with a limited upward movement and an eye at its upper end, and a rock shaft having a lifting arm with a limited downward movement and with a horizontal eye at its free end, of a U shape connecting pin having one leg provided with a head and extending through said horizontal eye and with its bent portion engaging the eye of said lock pin, the free leg of the connecting pin being substantially as long as the other leg and being inclined 15 away from such other leg.

3. The combination with a coupler of the Janey type having a lock pin with a limited upward movement and an eye at its upper end, and a rock shaft having a lifting arm 20 with a limited downward movement and

with a horizontal eye at its free end, of a connecting pin for the two eyes comprising a vertical leg provided with a head at its upper end, a partial eye portion at the lower end of such leg and a second leg extending upwardly to a point adjacent the head and inclined away from the vertical leg, and being of such length that said second leg still engages the eye of the lock pin when such pin is at its upper limit of movement 25 and the lifting arm is at its lower limit of movement.

In testimony whereof, I have hereunto subscribed my name this 19th day of Dec., 1921.

WILLIAM J. KNOX.
